UNITED STATES PATENT OFFICE.

EMIL R. DRAVER, OF RICHMOND, INDIANA.

DISK WHEEL.

1,378,332.

Specification of Letters Patent. Patented May 17, 1921.

Original application filed October 20, 1920, Serial No. 414,551. Divided and this application filed February 7, 1921. Serial No. 442,975.

To all whom it may concern:

Be it known that I, EMIL R. DRAVER, a citizen of the United States, residing at Richmond, in the county of Wayne and State of Indiana, have invented certain new and useful Improvements in Disk Wheels; and I do hereby declare the following to be a full, clear, and exact description of the invention, such as will enable others skilled 10 in the art to which it appertains to make and use the same.

My present invention relates to disk wheels that are equipped with pneumatic tires and has for its object to provide an 15 extremely simple and highly efficient means for affording ready access to the valve stem of the tire, from the outer side of the wheel, where the valve stem is on the inner side of the wheel disk. The present application 20 is filed as a division of my pending application S. N. 414,551, filed October 4, 1920.

In the accompanying drawings which illustrate the invention, like characters indicate like parts throughout the several 25 views.

Referring to the drawings:

Figure 1 is a side elevation of the tire-equipped disk wheel equipped in accordance with my invention, said wheel, as illustrated, being of the single disk type;

Fig. 2 is a vertical section taken on the line 2-2 of Fig. 1, some parts being in full;

Fig. 3 is a fragmentary view looking at the inner side of the disk and showing a 35 port cover in a port-closing position;

Fig. 4 is a section on the line 4-4 of Fig. 3; and

Fig. 5 is an elevation looking at the outer face of the detached port cover.

40 The numeral 6 indicates the flanged wheel hub; the numeral 7, the wheel disk; the numeral 8, the wheel rim; the numeral 9, the tire casing; and, the numeral 10, the inner tube, which latter has the customary valve 45 stem 11 projected radially inward through the rim 8 and the flange of the disk 7.

In the construction illustrated, the disk is provided with a charging port or passage 12 shown as round and located, approximately in line with the end of the valve 50 stem 11. This port 12 is normally closed by a round cover plate 13 that fits said port and is adapted to be seated against a flange or like portion 14 pressed inward from the 55 disk at the margin of said port.

In this arrangement, the cover plate 13 is arranged to be moved from its port-closing position by first drawing the same outward and then swinging the same toward one side of the port. To thus support said 60 cover plate, I provide an arm 15 which is pivotally connected to the wheel disk at its inner side at 16. At its free end, the arm 15 is loosely jointed to a small bolt 17, the threaded outer end of which is extended 65 through an axial perforation 18 in the cover plate 13 and is provided with a thumb nut 19, or the like. To prevent accidental rotation of the nut 19, the cover plate 13 is shown as provided with a slightly depressed 70 rectangular seat 20 in which the rectangular portion of the nut 19 is normally seated.

With this construction, the cover plate 13 may be drawn outward and then swung to one side so as to about half open the port 12 without removing said cover plate from the bolt 17. Hence, the port 12 should be made large enough to permit the charging tube to be connected to the valve stem 80 through the opening afforded by said port when but half open. However, if the nut 19 be removed, the port-closing plate may be entirely displaced from said port and, in that event, said port may be made smaller. This device is especially adapted for application to a single disk wheel, but may, nevertheless, be applied to the outer disk 85 of a double disk wheel. Said device is very simple, easily operated and efficient for the purpose had in view. It affords convenient 90 means for reaching a valve stem that is located on the inner side of a wheel disk.

Preferably and as shown, the arm 15 is made of flat spring steel, but, of course, it might be a more rigid or even an unyielding 95 element.

What I claim is:

1. A disk wheel having in its disk a port through which the valve stem of an applied tire may be reached, a displaceable cover 100 for said port mounted for outward opening movement, and an arm applied to the inner side of said disk, connected to said cover and normally holding the same in port-closing position.

2. A disk wheel having in its disk a port through which the valve stem of an applied tire may be reached, a displaceable cover 110 for said port mounted for outward opening movement, and an arm applied to the inner

- side of the said disk, connected to said cover and normally holding the same in port-closing position, said arm being pivoted for lateral swinging movements.
5. 3. A disk wheel having in its disk a port through which the valve stem of an applied tire may be reached, a displaceable cover for said port mounted for outward opening movements, an arm pivoted to the inner side 10 of said disk, and a threaded bolt connecting the end of said arm to said cover and normally holding the latter in a port-closing position.
4. A disk wheel having in its disk a port 15 through which the valve stem of an applied tire may be reached, a displaceable cover for said port mounted for outward opening movements, an arm pivoted to the inner side of said disk, and a threaded bolt connected 20 to the free end of said arm, extended through said cover and provided at its outer end with a nut engageable with said cover.
5. A disk wheel equipped with a pneumatic tire having a valve stem projected 25 through its rim inward of the wheel disk,
- said disk having a port approximately in line with said valve stem, a displaceable cover for said port mounted for outward opening movement, a spring arm applied to the inner side of said disk, a bolt loosely 30 connected to the free end of said spring arm and extended through said cover, and a nut applied to the outer end of said bolt and bearing against said cover, said cover and nut having normally engaging angular portions holding said nut against accidental rotation.
6. A disk wheel having in its disk a port through which the valve stem of an applied tire may be reached, an arm applied to one 40 side of said disk, a cover for said port adapted to be opened by movement in a direction away from said arm, and a connection extended from the free end of said arm through said port to said arm and serving 45 to normally hold said cover in a port-closing position.

In testimony whereof I affix my signature.

EMIL R. DRAVER.
